Primary Examiner — T Chase Nelson

Assistant Examiner — Kelly L Gross

(57) **CLAIM**

The ornamental design for a bottle piercing station for the transfer of fluids for use in laboratories, medicine and radiopharmacy as shown and described.

DESCRIPTION

1.2 : Front

1.3 : Left

1.4 : Right

1.5 : Top

1.6 : Perspective

The feature of the design is its shape; the design is a bottle piercing station for the transfer of fluids for use in laboratories, medicine and radiopharmacy, to be used to transfer fluids; view **1.6** best shows the essential features of the design. The portions of the bottle piercing station shown in broken lines form no part of the claimed design.

1 Claim, 5 Drawing Sheets
